(57) **CLAIM**

The ornamental design for a healthcare multitool wrench with spanner as shown and described.

DESCRIPTION

FIG. 1 is a perspective view of a healthcare multitool wrench with spanner showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a top side view thereof; and,

FIG. 7 is a bottom side view thereof.

The spanner shown in broken lines is not part of the ornamental design as claimed.

1 Claim, 2 Drawing Sheets
